UNITED STATES PATENT OFFICE.

CHARLES LEWIS, OF ST. LOUIS, MISSOURI.

HAIR COMB.

Application filed May 11, 1926. Serial No. 108,265.

My invention relates to improvements in hair combs.

Objects of my invention are to provide a comb which is adapted to be heated, and may be manipulated for applying various pressures upon the hair, during the combing operation, which is usually done while the hair is treated with an oil or wax, whereby the hair is straightened; to provide means whereby the hair will not be caught or nipped during the combing operation; to provide means whereby the device may be used as an ordinary comb with the usual stationary teeth; to provide means whereby each tooth of the comb is formed of teeth sections, so arranged that the hair can not pass between the teeth sections or each tooth, prior to their manual opening; to improve the construction of the comb in general, rendering it more efficient in use.

Other objects and advantages of the invention will be apparent during the course of the following description.

In the accompanying drawings, forming a part of this specification, and in which like numerals are employed to designate like parts throughout the same,

Figure 1 is a side elevation of a comb embodying my invention,

Figure 2 is a plan view of the same, parts broken away,

Figure 3 is a central vertical longitudinal section through the comb, parts in elevation,

Figure 4 is a plan view of the comb, parts in central horizontal longitudinal section,

Figure 5 is a perspective view of one head element,

Figure 6 is a transverse section through two head elements, showing the same separated,

Figure 7 is a similar view through the two head elements, showing the same assembled,

Figure 8 is an enlarged side elevation of a pair of teeth elements, and,

Figure 9 is a detailed section taken on line 9-9 of Figure 3.

In the drawings, wherein for the purpose of illustration, is shown a preferred embodiment of my invention the numerals 5 and 6 designate head sections, preferably formed of a metal, such as copper, or other material having a high heating conductivity. The head sections 5 and 6 are semi-cylindrical and their flat faces are assembled in sliding contact. The head section 6 has a shank section 7, and the head section 5 has a shank

section 8 which is also semi-cylindrical. Surrounding the shank sections 7 and 8 is a sleeve 9, and a hollow handle 10 is adapted to be inserted upon this sleeve, and to be clamped thereto. This handle is preferably provided with a band 11, and a screw 12 passes through an opening 13 formed in the elements 7, 9, 10 and 11. The shank section 7 is, therefore, rigidly secured to the sleeve 9 and handle 10 and the head section 6 is, therefore, relatively stationary, while the head section 5 is adapted to be shifted longitudinally with relation thereto.

The head section 5 is drawn rearwardly by means of a stiff compressible coil spring 14, mounted within the handle 10, and engaging the sleeve 9, and a ring or stop element 15, which surrounds the shank sections 7 and 8, but is attached to the shank section 8, only, by means of a screw 16 or the like, the shank section 7 being slidable therein.

The sleeve 9 is provided with a groove 17, receiving a band 18, carrying radial knuckles 20, between which is mounted the free end 21 of a bell crank lever 21, pivoted to the knuckles 20, as shown at 22. The free end of the bell crank lever operates within a notch or recess 23, cut in the shank section 8, as shown. The bell crank lever 21 is preferably equipped with a heat insulating handle 24. The numeral 25 designates a cap, covering the forward ends of the head sections 5 and 6, and rigidly attached to the head section 6 alone, by means of a screw 26. The cap 25 is provided at its bottom with a notch 27.

As more clearly shown in Figure 7, the head sections 5 and 6 have their inner faces cut away or beveled, providing outwardly diverging walls 28, whereby the edges of the straight contact faces 29 meet at a point 30, which is spaced inwardly a considerable distance from the periphery of the head sections. This is done, so that the hair 291 cannot come in contact with the sliding faces 29, for if it did, some of the hair might be caught or worked between these faces causing the hair to be nipped or pinched.

Formed integral with the movable head section 5, Figure 5, are sets of intermediate teeth sections 31 and an end tooth 32. These teeth sections and tooth 32 have their central longitudinal axes in alignment with the central longitudinal axis of the head formed by the head sections 5 and 6. These teeth sections and tooth are formed upon the in-

clined wall 28, and are provided at their bases with beveled faces 33, to slidably contact with the opposite inclined wall 28. The head section 6 is provided with a forward tooth 34 and teeth sections 35, integral therewith. These teeth sections and tooth are carried by the inclined wall 28 of the head section 6, and are so located that their central longitudinal axes are in alinement with the central longitudinal axis of the head formed by the sections 5 and 6 and also of the central longitudinal axes of the teeth 31. The teeth 35 are provided at their bases with beveled faces 36, to slidably contact with the inclined wall 28, of the head section 5. The teeth sections 31 and 35, interfit or overlap and each pair of teeth sections forms a tooth. Each pair of teeth sections have outer transversely curved or beveled faces 37 and their ends are preferably tapered, at 38. The teeth sections 31 and 35 are also preferably longitudinally curved and converge slightly outwardly in the longitudinal plane of the head, whereby the free ends of these teeth sections are always in firm engagement, preventing the passage of hair therebetween. The teeth sections 31 and 35 are resilient and the strength of the spring 14 is sufficient to overcome the combined resistance of any two or all the teeth sections, whereby all free ends of the teeth sections are held in contact, before the lever 20 is depressed. This is important, as some of the teeth sections may become slightly bent, and the adjacent teeth sections might not have a firm contact with each other, were it not for the fact that the teeth sections are resilient, longitudinally curved, and adapted to be compressed by the spring. The edges of the teeth sections, at their bases, as indicated at 39, are offset inwardly from the periphery of the head sections, whereby the hair cannot pass between the beveled faces 33 and 36 and the inclined walls 28.

In the use of the comb, the spring 14 normally retains the lever 20 elevated, and the head section 5 is retracted. This shifts the teeth section 31 into close relation to the teeth sections 35, whereby their free ends all firmly contact and the longitudinal bowed teeth sections are placed under tension. The comb may be heated as by being held over a lamp, stove or the like. It is obvious that the construction may be modified whereby the comb may be electrically heated. The comb may now be passed through the hair, as is done with the ordinary comb, and the hair will pass through the spaces 40, occurring between the curved or beveled outer faces of the pairs of teeth sections. When it is desired to exert additional pressure on the hair, while the same is arranged within the spaces 40, the lever 21 is depressed, and the teeth sections 31 are shifted forwardly with relation to the teeth sections 35, thus causing

the rounded or beveled faces of the teeth to contact with the hair. It is obvious that various degrees of pressure may thus be applied to the hair.

The invention is not restricted to the precise arrangement of the operating lever at the end of the head, as I contemplate changing this location. However, the construction given is the preferred arrangement.

It is to be understood that the form of my invention, herewith shown and described, is to be taken as a preferred example of the same, and that various changes in the shape, size and arrangement of parts may be resorted to without departing from the spirit or of my invention or the scope of the subjoined claims.

Having thus described my invention, I claim:—

1. A comb of the character described comprising relatively longitudinally movable head sections having inner sliding contact faces, teeth sections carried by the head sections, said head sections when assembled having a longitudinal recess at the bases of the teeth sections whereby the hair can not readily engage with the contact faces.

2. A comb of the character described comprising relatively longitudinally movable head sections constituting a head, sets of teeth sections carried by the head sections, said head sections when assembled having a recess adjacent to the bases of said teeth sections, and means to effect the relative movement between the head sections.

3. A comb of the character described comprising relatively longitudinally movable head sections having sliding walls, said head sections having outwardly diverging walls upon one side forming a longitudinal recess, when the head sections are assembled, sets of teeth sections carried by the head sections adjacent to the diverging walls, and means for effecting the relative longitudinal movement between the head sections.

4. A comb of the character described comprising relatively reciprocatory head sections, said head sections being provided with inclined walls forming a recess, when the head sections are assembled, sets of teeth sections formed upon the inclined walls, said teeth sections being provided at their bases with inclined faces to co-act with the inclined walls and means to effect the relative reciprocatory movement between said head sections.

5. A comb of the character described comprising a pair of relatively longitudinally movable head sections, sets of resilient teeth sections carried by the head sections, the teeth sections in the sets co-acting for producing teeth, means including a spring to effect the relative longitudinal movement of the head sections, said spring being sufficiently strong to overcome two or more pairs of the teeth sections.

6. A comb of the character described, comprising a pair of relatively longitudinally movable head sections, the sets of resilient teeth sections carried by the head sections, 5 the teeth sections in one set being arranged with relation to the teeth sections in the other set to produce pairs of co-acting teeth sections, the teeth sections in each pair converging toward their free ends, and 10 means to effect the relative longitudinal movement of the head sections including a spring to draw the teeth sections in said pairs toward each other.
7. A comb of the character described, comprising a pair of relatively longitudinally 15 movable head sections, sets of yieldable teeth sections carried by the head sections, the teeth sections in one set being arranged with relation to the teeth sections in the other set to produce pairs of co-acting teeth sections, the teeth sections in each pair converging toward their free ends, resilient means to move one head section in a direction to draw the teeth sections in said pairs together, and separate means to move such head section in an opposite direction.

In testimony whereof I affix my signature.

CHARLES LEWIS.
